(57) **CLAIM**

The ornamental design for a removably attachable lens, as shown and described.

DESCRIPTION

FIG. 1 is a front perspective view of a removably attachable lens according to a first embodiment of our design;

FIG. 2 is a front elevation view of the removably attachable lens of FIG. 1;

FIG. 3 is a rear elevation view of the removably attachable lens of FIG. 1;

FIG. 4 is a right elevation view of the removably attachable lens of FIG. 1;

FIG. 5 is a left elevation view of the removably attachable lens of FIG. 1;

FIG. 6 is a top elevation view of the removably attachable lens of FIG. 1;

FIG. 7 is a bottom elevation view of the removably attachable lens of FIG. 1;

FIG. 8 is a rear perspective view of the removably attachable lens of FIG. 1;

FIG. 9 is a front perspective view of the removably attachable lens of FIG. 1 showing additional environmental features that can be associated therewith; and,

FIG. 10 is a rear perspective view of the removably attachable lens of FIG. 1 along with the additional environmental features of FIG. 9.

Broken lines are environmental only and form no part of the claimed design.

Dash-dot lines adjacent un-shaded areas represent bounds of the claimed design and form no part of the claimed design themselves.
